UNITED STATES PATENT OFFICE.

FRANK LESTER CAMPBELL, OF CHELAN, WASHINGTON.

SHOE-SHINER'S CLAMP.

1,090,022.

Specification of Letters Patent. Patented Mar. 10, 1914.

Application filed April 18, 1913. Serial No. 761,995.

To all whom it may concern:

Be it known that I, FRANK L. CAMPBELL, a citizen of the United States, residing at Chelan, in the county of Chelan and State 5 of Washington, have invented new and useful Improvements in Shoe-Shiners' Clamps, of which the following is a specification.

Patrons of public shoe shining establishments frequently experience inconvenience 10 and difficulty in holding the foot in proper position during the shoe shining operation and as a result the foot is required to be frequently positioned upon the rest and often-times the shiner is required to use one 15 hand to hold the foot in place while the other hand is occupied in the shining or polishing operation.

The present invention provides means for securing the foot, thereby relieving the 20 patron of all strain incident to holding the foot in proper position and at the same time enabling the shiner to use both hands, with the result that the operation is expedited and all objection of the patron overcome.

25 The invention consists of the novel features, details of construction and combination of parts, which hereinafter will be more particularly set forth, illustrated in the accompanying drawings, and pointed out in 30 the appended claims.

Referring to the drawings, forming a part 35 of the specification, Figure 1 is a side view of a foot rest provided with securing means for the shoe embodying the invention. Fig. 2 is a front view of the parts shown in Fig. 1. Fig. 3 is a top plan view. Fig. 4 is a section on the line $x-x$ of Fig. 1. Fig. 5 is a horizontal section on the line $y-y$ of Fig. 1. Fig. 6 is a detail perspective view 40 of the clip, which is pivotally connected with the foot rest and to which the clamp levers are pivotally connected.

45 Corresponding and like parts are referred to in the following description, and indicated in all the views of the drawing, by the same reference characters.

The foot rest may be of any construction such as generally provided in public places for the accommodation and comfort of 50 patrons desiring to have their shoes polished or dressed. As shown the foot rest comprises a standard 1 and a block 2, the latter being shaped upon its upper side to conform approximately to the general outline of the 55 shoe and the heel of a shoe. A clip 3 has pivotal connection at its forward end with

the front portion of the part 2 of the foot rest and in turn has operating levers 4 pivoted thereto, said operating levers being provided at their upper ends with jaws 5 and 60 connected at their lower ends by means of a bow spring 6. The clip 3 is approximately of U form and has its side members or legs 7 extending along opposite sides of the foot rest, the lower portions of the legs 7 being 65 inwardly deflected so as to touch opposite sides of the standard 1. A tongue 8 projects forwardly from the horizontal portion of the clip 3 and is pivotally connected to a plate 9 which is secured to the front portion of the block 2. The pivot joint 10 between the parts 8 and 9 may be formed in any manner. Spaced ears 11 are provided at the lower ends of the legs or side members 7 of the clip 3 and receive the operating 70 levers 4 between them, said ears and operating levers being transversely pierced to receive pivot pins 12. The jaws 5 are of a length and shape to firmly grip the part of the sole immediately in front of the heel of 80 the shoe and opposite the hollow of the foot. The bow spring 6 is expansible and normally tends to force the lower ends of the levers 4 outward, with the result that the jaws 5 are pressed inward and compelled to 85 automatically grip the edge portions of the shoe sole when the foot is in position to have the shoe polished or dressed. A rod 13 is supported in the lower portions of the operating levers 4 and acts in conjunction 90 with a dog 14 to hold the operating levers and clip in the required angular position with the sole of the shoe gripped between the jaws 5.

Upon moving the lower ends of the 95 levers 4 toward the standard 1 the clip 3 is caused to turn upon the pivotal connection between the parts 8 and 9, thereby bodily carrying the jaws 5 upward. When moving the lower ends of the levers 4 away from the 100 standard 1 the clip 3 swings upon the pivot fastening 10 in a manner to lower the jaws 5. The levers 4 when adjusted are held in fixed relative position to the standard 1 by means of the dog 14 and rod 13, thereby 105 holding the jaws 5 at the required position so as to engage or release the sole of the shoe. The rod 13 having the levers 4 loosely connected therewith admits of such levers being operated to cause the jaws 5 either to 110 grip or release the shoe.

The dog 14 has its lower portion pro-

vided in its length with a plurality of notches 15 forming teeth which are adapted to engage the rod 13 in an adjusted position. The dog 14 is pivotally connected at its inner end to a plate 16 which is secured in any manner to a side of the standard 1, the pivotal connection being formed by means of a pin 17 or in any other convenient way. It is to be understood that the lower ends of the levers 4 and the standard 1 have such relation as to enable a clearance being had for the free operation of the levers to the proper working of the jaws 5. When the lower ends of the levers 4 are pressed inward the bow spring 6 is compressed and the jaws 5 are separated and when the levers 4 are released from all restraint the spring 6 tends to press the lower ends of the levers 4 apart and the jaws 5 together, thereby causing said jaws to grip the sole of the shoe that may be placed between them. The jaws may be raised or lowered by swinging the lower ends of the levers 4 toward or away from the standard 1. It is to be understood that the heels of the shoes vary in height, hence the soles occupy different relative positions when the foot is placed upon the block 2 of the foot rest, hence the advantage and necessity for adjustment to enable the jaws 5 to be raised or lowered so that they may properly and securely grip the sole of the shoe in position for polishing, dressing, or other treatment.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when de-

sired as are within the scope of the claims appended hereto.

Having thus described the invention what is claimed as new, is:—

1. In a shoe stand the combination of a 50 foot rest, operating levers having pivotal connection with the foot rest and provided with jaws to grip the sole of the shoe placed in position upon the foot rest, said jaws being bodily adjustable by a swinging movement of the levers toward and away from the foot rest.

2. In combination a foot rest, operating levers having pivotal connection with the foot rest and provided with shoe gripping 60 jaws which are adapted to be adjusted vertically bodily by a swinging movement of the levers toward or away from the foot rest, and means for securing the levers in the required position to hold the shoe gripping 65 jaws at the required elevation.

3. In combination a foot rest, a clip fitted to the foot rest and having pivotal connection therewith, operating levers pivotally connected to the clip and provided with shoe 70 gripping jaws which are adapted to be adjusted vertically bodily by a pivotal movement of the clip, and means for securing the operating levers in the required position.

4. In combination a foot rest, a clip having an extension by means of which it is pivotally connected to the foot rest, said clip embodying side members embracing opposite sides of the foot rest, operating levers pivoted to the side members of the clip and 80 provided with shoe gripping jaws, and means for securing the operating levers in required position for gripping the shoe placed in position upon the rest.

In testimony whereof I affix my signature in presence of two witnesses.

FRANK LESTER CAMPBELL.
